UNITED STATES PATENT OFFICE.

WILLIAM S. STOTHOFF, OF EASTON, PENNSYLVANIA, ASSIGNOR TO TIOGA STEEL AND IRON COMPANY, OF PHILADELPHIA, PENNSYLVANIA, A CORPORATION OF PENNSYLVANIA.

DESIGN FOR A TRUCK-WHEEL.

56,897.

Specification for Design.

Patented Jan. 4, 1921.

Application filed February 21, 1920. Serial No. 360,416. Term of patent 7 years.

To all whom it may concern:

Be it known that I, WILLIAM S. STOTHOFF, residing at Easton, in the county of Northampton and State of Pennsylvania, have invented a new, original, and ornamental Design for Truck-Wheels, of which the following is a specification, reference being had to the accompanying drawing, forming part hereof.

Figure 1 is a face view of a truck wheel, showing my new design; and

Fig. 2 is a view principally in section.

I claim:—

The ornamental design for a truck wheel, as shown.

WILLIAM S. STOTHOFF.
